(57) **CLAIM**

The ornamental design for a handle for wire insulation stripping tool, as shown and described.

DESCRIPTION

FIG. 1 is a first perspective view of a handle for wire insulation stripping tool;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The portion shown by broken lines is for illustrative purposes only and forms no part of the claimed design.
